(57) **CLAIM**

The ornamental design for a wire brush trimmer, as shown and described.

DESCRIPTION

FIG. 1 is a front, right, and top perspective view of a wire brush trimmer, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of a wire brush labeled **8** in FIG. 1.

The broken lines shown in the drawings are included for the purpose of illustrating portions of the wire brush trimmer that form no part of the claimed design.
